UNITED STATES PATENT OFFICE.

HAROLD S. SINES, OF CHICAGO, ILLINOIS, ASSIGNOR TO MINERALLAC ELECTRIC COMPANY, OF CHICAGO, ILLINOIS, A CORPORATION OF ILLINOIS.

PERIODICALLY-OPERATED MECHANISM.

1,309,427.

Specification of Letters Patent.

Patented July 8, 1919.

Original application filed January 19, 1915, Serial No. 3,021. Divided and this application filed February 24, 1919. Serial No. 278,788.

To all whom it may concern:

Be it known that I, HAROLD S. SINES, a citizen of the United States, residing at Chicago, in the county of Cook and State of Illinois, have invented a certain new and useful Improvement in Periodically-Operated Mechanism, of which the following is a full, clear, concise, and exact description, reference being had to the accompanying drawings, forming a part of this specification.

My invention relates to improvements in periodically-operated mechanism, and in order that it may be clearly understood, I have illustrated and described herein my invention embodied in a time switch such as is used for automatically closing and opening a power switch for supplying current to electric lights or other translating devices.

20 The objects of my invention are:

First: To provide a mechanism which comprises a member to be actuated periodically and at certain predetermined times, the means for thus actuating the member comprising a time-keeping mechanism having a main spring, a second spring, means actuated by the second spring and controlled by said clock mechanism for actuating said member, a motor, connections between the motor and the two springs for energizing these springs, the said connections comprising means for transmitting the energy of the motor to the springs in accordance with the deenergized condition of the springs.

35 Second: To provide a mechanism of the character described, in which the motor for energizing the springs is started and stopped by means controlled by the clock mechanism.

Third: To provide a mechanism comprising a clock mechanism having a main spring, a second spring for actuating a movable member, a motor for energizing said springs, the connections between the motor and the springs comprising a differential mechanism of such nature as to selectively transmit the energy of the motor to either or both of the springs in accordance with the condition of said springs.

Fourth: To provide a time switch embodying the mechanism having the characteristics set forth in the previous objects.

Other objects will appear as this description progresses, reference being had to the accompanying drawing, in which:

55

Figure 1 is a front elevation of my improved mechanism.

Fig. 2 is a transverse horizontal section, taken on line 2—2 of Fig. 1.

Fig. 3 is a transverse longitudinal section 60 taken on line 3—3 of Fig. 2, portions of the clock escapement mechanism being omitted.

Fig. 4 is a transverse horizontal section taken on line 4—4 of Fig. 3.

Fig. 5 is an enlarged sectional detail view 65 taken upon line 5—5 of Fig. 3, illustrating the devices which insure positive action of the switching mechanism illustrated in Figs. 2 and 3.

Fig. 6 is a plan view of the snap switch 70 which forms a part of the time switch mechanism.

Fig. 7 diagrammatically illustrates the circuit arrangements used in connection with my invention.

75

Similar reference characters refer to similar parts throughout the several views.

This application is a division of my application Serial No. 3021, filed January 19, 1915.

80

Referring first to Fig. 1 of the drawings, my invention comprises a supporting plate or base 20, which carries the plates 21, 22 and 23, disposed at right angles thereto. These plates are secured together and 85 spaced apart by suitable screws and posts as illustrated, the plates 21, 22, and 23 serving to support the larger portion of the time-keeping and switching mechanism. The plate or base 20 also supports plates or 90 shelves 24 and 25, between which is located an electric motor 26, which, as will presently be explained, operates to rewind or reenergize the springs for the time-keeping and switching mechanisms. Referring to Fig. 3, 95 reference character 26 indicates a shaft the upper end of which is journaled in the plate 21, and the lower end of which is journaled in the upper end of the shaft 27, the upper end of the shaft 27 being in turn journaled in the plate 22. The upper end of the shaft 27 is provided with a disk-like enlargement 28, to the upper side of which is riveted the drum 29, which incloses the spring 30, one

end of which is secured to the drum 29, as indicated at 31, and the other end of which is secured to the shaft 26, as indicated at 32. The shaft 26 passes freely through the upper side of the drum 29. From the above 5 description it will be clear that when the shaft 27 is rotated in the proper direction the spring 30 will be placed under tension and tend to rotate the shaft 26. The spur gear 33 is connected to the upper end of the shaft 26, and is provided adjacent its edge 10 with a pin 34, the function of which will be referred to later on.

As is most clearly illustrated in Fig. 2, 15 the spur gear 33 meshes with a pinion 35, fixed upon a shaft 35^a, and from the shaft 35^a motion is transmitted through a train 20 comprising gears 36, 37, 38, 39, pinion 40, gear 50, and pinion 51, to a shaft 52, which shaft is in turn operatively connected with 25 a marine escapement mechanism 53, illustrated in Fig. 1. The details of the escapement 30 mechanism 53 do not form any part of my present invention, and inasmuch as any desired form of escapement may be employed, the escapement mechanism in question has not been illustrated in all its details. It will suffice to say that assuming the shaft 28 to be held stationary and the spring 30 to be under tension, the gear 33 will be rotated at a constant 35 rate, due to the clock train and escapement mechanism just described.

Fixed upon the shaft 35, as indicated in dotted lines in Fig. 2, is a bevel gear 54, 35 which in turn meshes with a corresponding bevel gear 55, fixed upon an arbor, which at its outer end carries a minute hand 56, which when the arbor is rotated is adapted to travel over a suitable clock dial 57 in the usual 40 manner. Disposed upon the arbor just referred to is the sleeve 58 which carries the usual hour hand 59. Motion is transmitted from the arbor to the sleeve 58 through a suitable reducing train illustrated in Fig. 2 45 and comprising a pinion 60 fixed relatively to the arbor, a gear 61, a pinion 62 fixed with respect to the gear 61, and gear 63 secured to the sleeve 58.

It will be clear from the above description 50 that the mechanism just described merely constitutes a time-keeping mechanism of which the spring 30 is the main spring. I will now describe the mechanism which actuates the switch to open and close the power 55 circuit which transmits the current to any desired translating device, this switch being the "actuated member" of my invention when broadly considered. In Fig. 6 I have shown a plan view of the switch 64 which 60 for the purpose of this invention is merely conventionally illustrated as being of the ordinary rotary, snap-switch type. The details of these switches are well understood, and need not be described herein. The shaft 65 of this switch extends upwardly and is

journaled in the plate 23, through which it extends, the upper end of the shaft 65 being provided with a bore which forms a bearing for the lower end of the shaft 27, and a spur gear 66 is loosely mounted upon the upper 70 end of the shaft 65. A drum 67 is likewise loosely mounted upon the upper end of the shaft 65 and riveted as shown, or otherwise secured, to the gear 66, so as to rotate therewith. One end of the spring 68 within the 75 drum 67 is secured to the shaft 65 as indicated at 69, and the other end thereof is secured to the wall of the drum 67 as indicated at 70. It will therefore be clear that when the spring 68 is placed under tension it will 80 tend to rotate the shaft 65 and consequently the movable contacts 71 of the rotary switch. A spur gear 72 is secured to the shaft 65 and meshes with a pinion 73 on the shaft 74. A gear 75 carried by the shaft 74 meshes with 85 a pinion 76 which is secured to the shaft 77. A winding plate 78 is secured to the shaft 77. An escapement plate 79 is also secured adjacent the upper end of the shaft 65, and is controlled by an escapement mechanism 90 presently to be described, to permit the shaft 65 to intermittently or periodically rotate to open and close the switch 64, the time of the opening and closing of the switch 64 being controlled by the clock mechanism in the 95 manner about to be described. The escapement plate 79 is held against rotation by the escapement mechanism.

I have now described the clock mechanism and the switch-actuating mechanism, each of 100 which, as has been seen, comprises a spring for actuating the same. I will now describe the means by which these springs are wound or kept in an energized condition.

Referring to Fig. 1, it will be seen that the 105 shaft of the motor 26 is provided with a worm 80, meshing with the worm gear 81, which has fixed with respect thereto a bevel gear meshing with the bevel gear 82 fixed upon the lower end of the shaft 83, vertically 11 disposed in suitable bearings and provided at its upper end with a spur gear 84. A shaft 85 is rotatably mounted in the plate 23, and extends loosely through the pinion 86 and the lower side of the differential bracket 87, 11 and is provided at its upper end with a bevel gear 88, and at its lower end with a spur gear 84', meshing with the gear 84. The pinion 86 is rotatably secured to the differential bracket 87 and meshes with the 1 spur gear 66. A shaft 89 has its upper end rotatably mounted in the plate 22, and its lower end extends through the upper side of the differential bracket 87 and is provided with a bevel gear 90. The bevel gears 88 and 90 mesh with opposite sides of the bevel gears 91, which are rotatably mounted on the sides of the differential bracket 87. The spur pinion 93 is rotatably mounted on the upper side of the differential bracket 87 and 1

meshes with the spur gear 94, which is keyed to the lower end of the shaft 27, the spur pinion 93 being secured to the shaft 89.

From the above description it will be seen that when the springs 30 and 68 have become unwound or deenergized and the shaft 83 is rotated in the direction of the arrow A the shaft 85 will be rotated in the opposite direction, and there will be a tendency for the differential bracket 87 to rotate. This tendency will, however, be resisted by the tension of the spring 68 exerted through the gear 66 and the pinion 86, in the event that the tension of the spring 68 is greater than the tension of the spring 30. Under this condition the energy of the motor will be transmitted to the spring 30 through the shaft 83, gears 84 and 84', shaft 85, bevel gear 88, bevel gears 91, bevel gear 90, shaft 89, spur pinion 93, spur gear 94, shaft 27, and drum 29. As soon as the tensions of the two springs become equal both springs will be wound simultaneously. If it should happen at the beginning of the winding operation that the tension of the spring 68 is less than that of the spring 30, the spur pinion 93, and consequently the bevel gear 90, will be held stationary, and as a result of this differential, bevel gears 91 will be rolled about their axes upon the bevel gear 90 and carry the differential bracket with them, and therefore cause the spur pinion 86 to rotate. The motion of the spur gear 86 will be transmitted to the spring 68 through the drum 67 and the spur gear 66. As soon as the tension of the two springs becomes equal, continued rotation of the shaft 83 will cause simultaneous winding or energizing of both springs. I have therefore provided means for selectively transmitting the energy from the motor to the springs 30 and 68 in accordance with the energized or deenergized condition of these springs,—that is, if one of the springs is deenergized more than the other, the energy of the motor will be transmitted to this spring, and vice versa; or if both of the springs are deenergized to the same degree, then both of the springs will be simultaneously energized by the motor.

Mounted upon the bracket 100, as is most clearly illustrated in Fig. 1, is a disk 101 provided with peripheral teeth meshing with a pinion 102. The pinion 102 just referred to is fixed upon a shaft 103, upon which is also fixed a bevel gear 104 meshing with a bevel gear 105 fixed upon the shaft 35^a to the clock train previously described. It will be understood, therefore, that the disk 101 is driven at a constant rate. Formed in the disk 101 near the periphery thereof are a plurality of apertures 106 which may be numbered as indicated if desired. The apertures 106 are arranged to receive pins 107, which, as will presently be described, serve to control in part the operation of the snap

switch mechanism. The apertures 106 are preferably numbered as indicated in Fig. 1 of the drawings, and the disk 101 is preferably colored on one side as indicated by the shade lines in Fig. 1, to distinguish those apertures corresponding to the hours of the night from those corresponding to the hours of the day. The plate 23 supports a block 108 which serves as a bearing for the shaft 103 that transmits motion from the time-keeping mechanism to the disk 101.

Keyed to the shaft 65 is an escapement plate 110 adapted to coöperate with the lever 111, pivoted at 112 to the plate 23. The escapement plate 110 is provided with four notches 113, each arranged when in position adjacent the lever 111 to coöperate with a lug 114 carried by the lever 111. Extending upwardly from the lever 111 is a post 115 to which is pivoted an arm 116. This arm, as shown, is arranged to extent outwardly so as to coöperate with the time-actuated disk and pins 101 and 107 respectively. A spring 117 is interposed between the arm 116 and the lever 111 to retain the parts in the position illustrated in the drawings. Carried by the post 115 is a flat spring 118 arranged to abut against the post 115 to hold the lever 111 in position to lock the escapement plate 110. A pin 119 is arranged to limit the movement of the lever 111 when the escapement is caused to operate, as will be described presently.

When the adjustable pin 107 engages the free end of the arm 116 and moves the same toward the right (Fig. 4), the lever 111 will be caused to disengage the escapement plate 110. As soon as this disengagement of the lever and plate takes place, the plate will be rotated by the spring 68, which has already been described as secured to the shaft 65. As the plate 110 rotates in the direction indicated by the arrow, the arm 116 is drawn inwardly by the spring 117, the arm riding on the periphery of the escapement plate. This motion imparted to the arm 116 enables the end of the arm to move away from the teeth of the actuating pin 118 and to return again to its normal position in the rear of the pin. As the escapement plate 110 rotates, the succeeding notch will, of course, be caught by the lug 114 to lock the shaft 65 until again released by a second pin 118.

Thus far I have described the time-keeping mechanism, the switching mechanism, the escapement mechanism which controls the operation of the switching mechanism, and the differential means for winding the springs driving the time mechanism and the switch mechanism respectively.

I will now describe the means which I employ for controlling the motor which actuates the spring-winding mechanism.

The circuit for the motor 26 is controlled by suitable switching mechanism illustrated

most clearly in Figs. 2 and 3. Mounted in the plates 21 and 22 is a shaft 120 having fixed thereon a four-toothed cam 121. Carried by the plate 22 is a pair of switch springs 122 and 123, which switch springs are provided with coöperating contact points 124 and 125. Disposed adjacent the switch spring 123 is a third spring 126 which is provided with an offset free end 127 coöperating with the cam 121, and carried by the switch spring 123 and interposed between the springs 123 and 126 is a block of insulation 128 which supports the said springs 123 and 126. It will be seen that when the offset portion 127 of the spring 126 is in the space between the pair of teeth of the cam 122, as illustrated in Fig. 2, the switch springs 122 and 123 will be in open position, but that when the cam 121 is operated to cause the portion 127 of the spring 126 to ride upon one of the teeth of the cam, the switch springs will be moved to closed position.

Fixed upon the shaft 120 and disposed adjacent the spur gear 33 is a disk 129 provided with four peripheral teeth 130. The disk 129 is so disposed that normally when the gear 33 is rotated the pin 34 carried thereby will engage one of the teeth 130 of the disk 129 and advance the shaft 120 to bring the cam 121 in position to close the switch springs 122 and 123. Due to the fact that the spur gear 33 forms a part of the clock train driven by the spring 30, it will be seen that each time the gear 33 is turned through one revolution the shaft 120 will be advanced one step, provided the disk 129 is in such an angular position that one of its teeth may be engaged by the pin 34. The length of time required to turn the gear 33 through one revolution is not material, but the several parts of the clock mechanism should be so related that the gear 33 will be turned through one revolution before the spring 30 has run down to any considerable extent.

Fixed upon the shaft 120 and disposed below the disk 129 is a second disk 131 provided with peripheral teeth 132. The peripheral teeth 132 are angularly disposed with relation to the teeth 130 of the disk 129, as is most clearly illustrated in Fig. 2. It will be seen, therefore, that if the several parts are in the positions illustrated in Fig. 1, and the disk is advanced one step, the cam 121 will operate to close the switch springs 122 and 123 and thereby close the circuit for the motor 26. If the disk 131 is then advanced one step, the cam 121 will be operated to permit the switch springs 122 and 123 to move to open position. The pin 34 carried by the spur gear 33 is arranged to advance the disk 129 one step for each revolution of the spur gear 33, provided the teeth of the disk 129 are in the proper angular positions.

I shall now describe the mechanism for advancing the disk 131. As is most clearly illustrated in Fig. 3, the shaft 26 has fixed thereto a worm 133 coöperating with a gear 134 mounted upon a shaft 135 bearing in plates or brackets 136 which are supported by the drum 29. Also mounted in the plates or brackets 136 is a shaft 137 having fixed thereon a pinion 138 meshing with the gear 134, and fixed upon one end of the shaft 138 is an arm 139, which, when the spring 30 is in full wound condition, assumes the position illustrated in full lines in Fig. 3. From the foregoing description it will be seen that when the shaft 26 is operated by the spring 30, the shaft 138 and arm 139 will be rotated in a clockwise direction (Fig. 3). It will be understood that at all times except when the spring 30 is being rewound the drum 29 will be stationary, and therefore the amount of displacement of the arm 139 which occurs due to the coöperation between the worm 133 and the gear 134 will be directly proportional to the energy lost by the spring 30 in driving the shaft 26 and parts connected therewith.

Assuming the several parts previously described to be in the positions illustrated in the drawings, when the spur gear 33 has been turned to bring the pin 34 into engagement with one of the teeth of the disk 131, the cam while associated with the switch springs 122 and 123 will be operated to close the switch springs and thus close the circuit for the motor 26. If there is sufficient current in the motor circuit to cause the operation of the motor, the motor will operate through the shaft 83, the differential mechanism and spur gear 94, to drive the drum 29 in the direction of the arrow B in Fig. 4. When this takes place the drum 29 is rotated in the same direction, inasmuch as it is fixed with respect to the gear 94, and the spring 30 is rewound. When the drum 29 is turned as described, the plates or brackets 136 of the gears supported thereby are turned about the worm 133, and consequently the arm 139 is turned in a counter clockwise direction. As soon as the drum 29 has been turned an amount sufficient to restore in the spring 30 the energy previously expended, the arm 139 will have assumed its original position indicated in full lines in Fig. 2. After the arm 139 has been moved to its horizontal position and is moved past the disk 131, the arm will engage one of the teeth of the disk and advance the shaft 120 and cam 121 to permit the switch springs 122 and 123 to open. Upon returning to normal position the operation just described is repeated. If it should happen that the circuit for the motor 26 is temporarily out of commission when the switch springs are moved to closed position, rewinding of

the spring 30 does not occur immediately. The spring 30, however, continues to drive the clock train and rotate the arm 139 in a clockwise direction. When the motor circuit becomes operative the motor starts to operate and continues to wind the spring 30 until the arm 139 has been returned to normal position. After the arm 139 has assumed its normal horizontal position, the disk 131 is advanced one step and the cam 121 operates the switch springs 122 and 123 to open the motor circuit as previously described.

Inasmuch as the advancement of the disks 129 and 131 sometimes occurs quite slowly, I find it desirable to provide some means to cause quick opening and closing of the switch springs 122 and 123 in order to avoid sparking at the contact point. I therefore provide the shaft 120 with a star wheel 140, most clearly illustrated in Fig. 5. The star wheel 140 is provided with eight teeth, and coöperating therewith is a roller 141 mounted upon the free end of the lever arm 142 pivoted to the plate 22. Associated with the arm 142 is a spring 143 which normally tends to force the roller 141 into engagement with the star wheel 140. It will be seen that the shaft 120 may be slowly advanced until the roller 141 has passed over one of the teeth of the star wheel. Then the spring 143 will force the roller 141 between a pair of the teeth of the star wheel and quickly advance the shaft 120 through the remainder of its one step advancement to effect the opening and closing of the springs 122 and 123 as the case may be.

In Fig. 7 of the drawings several accompanying elements have been illustrated quite diagrammatically. It will be seen that the snap switch controls the circuit for a lamp load and that the rewinding motor is operatively connected with the features which are arranged to be connected with the lamp load. It is not essential, however, that the rewinding motor be supplied with energy in this manner, but on the other hand, the motor may be equipped with an independent source of current as illustrated in dotted lines.

While I have described the details of the preferred embodiment of my invention, it is to be understood that my invention is not limited to these details but is capable of other adaptations and modifications within the scope of the appended claims.

Having thus described my invention what I claim is:—

1. The combination with a clock mechanism having a main spring, of a switch, a second spring, means actuated by said second spring and controlled by said clock mechanism for opening and closing said switch, a motor, connections between said

motor and said springs, including differential means for energizing said springs, and means controlled by said clock mechanism for starting and stopping said motor.

2. The combination with a clock mechanism having a main spring, of a switch, a second spring, means actuated by said second spring and controlled by said clock mechanism for opening and closing said switch, a motor, connections between said motor and said springs, including differential means for energizing said springs, and means for starting and stopping said motor.

3. The combination with a clock mechanism having a main spring, of a switch, a second spring, means actuated by said second spring and controlled by said clock mechanism for opening and closing said switch, a motor, and connections between said motor and said springs, including differential means for energizing said springs.

4. The combination with a clock mechanism having a main spring, of a switch, a second spring, means actuated by said second spring and controlled by said clock mechanism for opening and closing said switch, a motor, permanent connections between said motor and said springs for energizing said springs, the said connections including means for selectively transmitting the energy of said motor to said springs in accordance with the deenergized condition of said springs, and means controlled by said clock mechanism for starting and stopping said motor.

5. The combination with a clock mechanism having a main spring, of a switch, a second spring, means actuated by said second spring and controlled by said clock mechanism for opening and closing said switch, a motor, permanent connections between said motor and said springs for energizing said springs, the said connections including means for selectively transmitting the energy of said motor to said springs in accordance with the deenergized condition of said springs, and means for starting and stopping said motor.

6. The combination with a clock mechanism having a main spring, of a switch, a second spring, means actuated by said second spring and controlled by said clock mechanism for opening and closing said switch, a motor, connections between said motor and said springs for energizing said springs, the said connections including means for selectively transmitting the energy of said motor to said springs in accordance with the deenergized condition of said springs, and means for starting and stopping said motor.

7. The combination with a clock mechanism having a main spring, of a switch, a second spring, means actuated by said sec-

- 6
- ond spring and controlled by said clock mechanism for actuating said switch, a motor, connections between said motor and said springs for energizing said springs, the said connections including means for selectively transmitting the energy of said motor to said springs in accordance with the deenergized condition of said springs, and means for starting and stopping said motor.
8. The combination with a clock mechanism comprising a main spring, of a member to be actuated, a second spring, means actuated by said second spring and controlled by said clock mechanism for actuating said member, a motor, and connections between said motor and said springs for energizing said springs comprising means for selectively transmitting the energy of said motor to said springs in accordance with the deenergized condition of said springs.
9. The combination with a mechanism having a main spring, of a switch, a second spring, a movable element actuated by one of said springs and controlled by the other of said springs, a motor, connections between said motor and said springs for energizing said springs, comprising means for selectively transmitting the energy of said motor to said springs in accordance with the tension of said springs, and means controlled by one of said springs for causing said motor to energize said springs.
10. The combination with two mechanisms each having a driving spring, one of said mechanisms being controlled by the other, of a motor for energizing said springs, and driving connections between said motor and said springs for selectively energizing said springs in accordance with the deenergized condition of said springs. 40
11. The combination with two mechanisms each having a driving spring, of a motor for energizing said springs, and driving connections between said motor and said springs for selectively energizing said springs in accordance with the deenergized condition of said springs. 45
12. The combination with two mechanisms each having a driving spring, of a means for energizing said springs, and driving connections between said energizing means and said springs for selectively energizing said springs in accordance with the deenergized condition of said springs. 50
- In witness whereof, I hereunto subscribe my name this 13 day of February, 1919.
